UNITED STATES PATENT OFFICE

ARTHUR D. PEARSON, OF CHICAGO, ILLINOIS

DESIGN FOR A PIN-BALL AMUSEMENT GAME DEVICE

Application filed December 5, 1932. Serial No. 46,310. Term of patent 3½ years.

To all whom it may concern:

Be it known that I, ARTHUR D. PEARSON, a citizen of the United States, and a resident of the city of Chicago, in the county of Cook and State of Illinois, have invented a new, original, and ornamental Design for a Pin-Ball Amusement Game Device, of which the following is a specification, reference being had to the accompanying drawing, forming part thereof.

In the drawing:

Fig. 1 is a plan view of a pin-ball amusement game device, showing my design.

Fig. 2 is a side elevational view thereof.
I claim:

The ornamental design for a pin-ball amusement game device, as shown and described.

Signed at Chicago, in the county of Cook and State of Illinois, this 2nd day of December, 1932.

ARTHUR D. PEARSON.
